CLAIM

I claim the ornamental design for a ballast room cover for a light fixture, as shown and described.

DESCRIPTION

FIG. 1 is a bottom perspective view of the ballast room cover for a light fixture;

FIG. 2 is a top perspective view thereof;

FIG. 3 is a top view thereof;

FIG. 4 is a bottom view thereof;

FIG. 5 is a front view thereof;

FIG. 6 is a rear view thereof;

FIG. 7 is a left view thereof; and,

FIG. 8 is a right view thereof.

1 Claim, 8 Drawing Sheets
